UNITED STATES PATENT OFFICE.

CASPAR S. DAVIDIAN, OF LAWRENCE, MASSACHUSETTS.

MACHINE FOR MAKING CONCRETE BLOCKS.

1,207,509.

Specification of Letters Patent. Patented Dec. 5, 1916.

Application filed June 30, 1915. Serial No. 37,779.

To all whom it may concern:

Be it known that I, CASPAR S. DAVIDIAN, a citizen of the United States of America, and a resident of Lawrence, in the county of 5 Essex and Commonwealth of Massachusetts, have invented certain new and useful Improvements in Machines for Making Concrete Blocks, of which the following is a specification.

10 The present invention relates to machines for molding building blocks of concrete or some similar material and has for its object the provision of a machine of this class which will be very effective in operation although constructed in a comparatively simple manner with few operating parts.

One of the objects of the invention is to provide means whereby the blocks may be withdrawn from the mold without injury to 20 the exposed ornamental faces of the block.

Another object of the invention is to locate the face plate of the mold at the bottom thereof immediately beneath the tamping devices so that when the latter are 25 operated the material will be forced directly at said face plate and a more compact and better finished face of the block will result.

The invention consists in certain novel features of construction and arrangement 30 of parts which will be fully understood by reference to the description of the drawings and to the claims hereinafter given.

Of the drawings: Figure 1 represents a plan of a machine embodying the principles 35 of the present invention. Fig. 2 represents a front elevation of a portion of the same. Fig. 3 represents a side elevation of the same. Fig. 4 represents a horizontal section of a portion of the same. Fig. 5 represents 40 a side elevation of a portion of the same with the face plate tipped into substantially vertical position, and Fig. 6 represents a sectional detail through a portion of the mold.

Similar characters designate like parts 45 throughout the several figures of the drawings.

In the drawings, 10—10 are two side frames connected by the girts 11. Each side frame 10 is provided at the rear thereof with an 50 upwardly extending projection 12, to which is secured a vertical back plate 13. This back plate has pivoted at 14 to opposite ends thereof the end plates 15 normally positioned perpendicular to the back plate 13, but adapted to be moved outwardly about the pivots 14 into the position shown at the

left of Fig. 4 of the drawings. The front upper end of each of the end plates 15 is provided with a projection 16. Supported upon the side frames 10 is a face plate 17 60 having a panel 18 in its upper face. This face plate 17 is pivoted at 19 to the side frames 10 and has upwardly extending lugs 20 at its forward end, said lugs being substantially perpendicular to the upper face of 65

said plate 17. These lugs 20 are adapted to position a removable pallet 21 the height of which is substantially the same as that of the vertical back plate 13 and the end plates 15. The opposite ends of the pallet 21 are 70 reduced in height as at 22, these reduced ends projecting beneath the lugs 16 on the pivoted end plates 15. When the pallet 21 has been vertically positioned by means of the lugs 20 and the end plates 15 have been 75

reduced against the shoulders 23 on the opposite ends of said plate, a rectangular frame 24 is placed around the back plate 13, end plates 15, and pallet 21, thus forming a 80 rectangular mold to receive the material from which a stone is to be formed. This rectangular frame 24 has corner members 25 which rest upon the upper edges of the mold formed by the back plate 13, end plates 15, and pallet 21, so that the walls of said 85

rectangular frame extend upwardly above the upper edges of the mold as shown in Figs. 2 and 3 of the drawings. The material is placed within the mold, thus formed, and then tamped by means of the separated 90 tamping members 26 the upper ends of which bear against the laterally extending flanges 27 formed upon a reciprocating member 28, the opposite ends of which are provided with bearings through which extend 95 the vertical rods 29 secured to brackets 30 fastened to the side frames 10. The upper ends of the rods 29 are connected by means of a tie 31 between which and the reciprocating member 28 are interposed springs 32. 100

In tamping the material in the mold the operator seizes the member 28 and depresses it so that the separated tamping members 26 come into contact with the material and force it directly toward the face plate 17 105 and into the panel 18 formed therein. This movement of the tamping devices directly toward the face plate 17 insures a more compact and better finished face to the stone being formed.

When the material has been sufficiently tamped, a portion thereof will extend above

the upper edges of the mold. The operator then seizes the rectangular frame 24 and lifts it sufficiently to disengage it from the pallet 21 and permits it to move toward the rear of the machine, the lower edge of the front wall scraping the surplus material above the upper edges of the mold and depositing such surplus material in the rear of the machine. In order to lighten the labor the rectangular frame 24 is provided with rearwardly extending rods 33 extending through bearings in the brackets 34 formed upon the side frames 10. Each rod 33 is provided with adjusting members 35 between which and the bracket 34 is interposed a spring 36, this spring having sufficient tension to withdraw the rectangular frame 24 from above the mold into the position shown in dotted lines at 37 in Fig. 3 of the drawings. The end plates 15 are then moved outwardly about their pivots 14 into the position shown at the left of Fig. 4 of the drawings. The operator then seizes the handle 38 secured to the face plate 17 and swings the face plate upwardly about its pivot 19 into a substantially vertical position. The forward ends of the side frames 10 are provided with slightly inclined supporting faces 39 on which the pallet 21 is deposited at the completion of this swinging movement of the face plate 17.

Owing to the inclination of the supporting portions 29 of the side frames 10 the stone just formed will be thrown slightly forward so that its panel will be separated and removed from the depression 18 in the face plate 17. The pallet 21 is then lifted with the stone thereon and deposited in some suitable place where it may become hardened and ready for use. Each end plate 15 is provided with a depression 40 adapted to form a panel in the end of the stone when desired. In case it is desired that one end of the stone should be perfectly flat without a panel a filling block 41 is provided to fit the depression 40, this block being secured in position by a bolt 42 extending through said block and end plate 15 and having a nut 43 threaded to its outer end. The back plate 13 is provided with a plurality of sets of projections 44 extending slightly into the mold, each pair of these projections being separated a distance equal to the spaces between the tamping members 26. The pallet 21 is provided with a plurality of similar projections 45 disposed directly opposite to the sets of projections on the back plate 13. When it is desired to form smaller stones in the mold, filling blocks 46 are disposed in the depression 18 in the face plate 17 and secured in position by means of bolts 47 extending through the face plate 17 and having nuts 48 threaded to the outer ends thereof. The block 46 having been positioned in this manner a

dividing plate 49 is positioned between the pairs of projections 44-45 as indicated in Fig. 6 of the drawings. When the tamping members 26 are depressed the dividing plate 49 will enter the space between two adjacent tamping members. When the filling blocks 46 are not in use the securing bolts 47 are retained in position in the face plate 17 by means of the nuts 48 as indicated at 50 in Fig. 6 of the drawings. It is obvious that by a device constructed as herein shown a stone may be formed of full length in the mold, two stones of half length may be formed, or there may be formed at a single operation a half length and two quarter lengths, or a half length, a quarter length, and two eighth lengths.

It is also apparent that by providing additional projections 44-45 to the vertical back plate 13 and the plate 21, other sizes may be formed if desired.

The machine is very simple in construction and very effective in its operation, making it possible to form an artificial stone very quickly with very little labor on the part of the operator.

It is believed that the operation and many advantages of this invention will be fully understood from the foregoing description.

Having thus described my invention, I claim:

1. In a device of the class described, the combination of a frame having a vertical plate; end plates pivoted to the ends of said vertical plate; a face plate pivotally mounted upon said frame and provided with lugs perpendicular to the face thereof; a pallet adapted to be positioned by said lugs; a rectangular frame for retaining said vertical plate, end plates, and pallet in normal position to form a mold; brackets secured to the rear of said frame; rods secured to said rectangular frame and extending through said brackets; springs surrounding said rods; and adjustable members on said rods for regulating the tension of said springs.

2. A device of the class described, comprising a frame having a vertical plate, end walls pivoted to the ends of said vertical plate, a spaced plate pivotally mounted upon the said frame and provided with lugs perpendicular to the face thereof, a pallet adapted to be positioned by the said lugs, a rectangular frame for retaining said vertical plate, end plates and pallet in normal position to form a mold, and resilient automatic retracting means for the said frame when released, the path of movement of said frame being in the plane of the top edge of the mold.

3. A block molding machine comprising a frame having inclined supporting faces and a vertical plate, end plates pivoted to the said vertical plate, a face plate pivotally mounted upon the said frame adjacent said

faces and provided with perpendicular lugs, a pallet adapted to be positioned by said lugs and arranged upon said inclined faces when the mold is open, a rectangular frame 5 for receiving said vertical plate, end plates and pallet in normal position to form a mold, and automatic means for moving said rectangular frame to the rear of the machine when disengaged from said plates and pallet. 10 4. A block molding machine comprising a frame having a vertical plate, end plates pivoted to the end of said vertical plate, a face plate pivotally mounted upon said frame and provided with lugs perpendicular 15 to the face thereof, a pallet adapted to be positioned by the said lugs, a removable rec-

tangular frame adapted to fit over the upper edges of said vertical plate, end plates and pallet to form a mold, interior corner members upon said rectangular frame seated 20 upon said mold with the side and end walls of the rectangular frame extending above the upper edges of said mold, and automatic shifting means for said rectangular frame when released from the mold. 25

Signed by me at 4 Post Office Sq., Boston, Mass., this 24th day of June, 1915.

CASPAR S. DAVIDIAN.
